UNITED STATES PATENT OFFICE.

JOSEPH E. WATTS, OF LAWRENCE, MASSACHUSETTS.

PRESSURE-REGULATOR.

SPECIFICATION forming part of Letters Patent No. 240,060, dated April 12, 1881.

Application filed March 8, 1881. (No model.)

To all whom it may concern:

Be it known that I, JOSEPH E. WATTS, a citizen of the United States, residing at Lawrence, in the county of Essex and State of Massachusetts, have invented certain new and useful Improvements in Pressure-Regulators; and I do hereby declare the following to be a full, clear, and exact description of the invention, such as will enable others skilled in the art 10 to which it appertains to make and use the same, reference being had to the accompanying drawing, and to letters or figures of reference marked thereon, which forms a part of this specification.

15 This invention relates to "pressure-regulators," so called, for governing the pressure of steam, gas, or other fluids or liquids, in order that a uniform pressure may be obtained in the delivery or distributing pipe or drum, 20 as against irregularities of pressure in the supply-pipe.

A notable instance of the class of regulators to which my present improvements pertain is shown in Letters Patent of the United States 25 issued to me on the 13th day of April, 1875, and reissued March 12, 1878, in which the stem or spindle of the regulating-valve is supported at its lower end upon an elastic diaphragm, and is properly connected to a weighted lever 30 or a spring, which acts to open or close the valve in consonance with variations in the pressure in the delivery or distributing pipe or drum, or the apparatus supplied with fluid which the valve is designed to govern.

35 In this class of regulators, if the diaphragm, from constant use or other cause, should give out or burst, the valve will be opened wide by the weighted lever, and steam, at full boiler-pressure, will be admitted to the apparatus 40 supplied with steam through the regulator—such, for instance, as the steam-cylinders of slashers in cotton-mills, drying-machines in print-works, and the like. Under these conditions the cylinders are subjected to a great 45 and sudden pressure, which, in some cases, causes them to burst or explode.

The object of my invention is to remedy this difficulty, and this I accomplish by combining with the valve, valve-stem, and diaphragm a piston (of less area than the diaphragm) attached to the stem and contained

in a chamber or cylinder above the diaphragm, the said piston fitting the cylinder loosely, so as to permit water to leak past it, one side or the other, according to the varying movements 55 or pulsations of the diaphragm. Owing to the loose fitting of the piston, the pressure of the water on both its faces is practically the same so long as the diaphragm remains tight and whole, and consequently it is the diaphragm 60 which controls the valve; but if from any cause the diaphragm should be torn or burst the water will at once run from the regulator and the steam will act on the upper face of the piston, forcing it down with superior pressure, 65 and consequently closing the valve.

The nature of my improvement and the manner in which the same is or may be carried into effect will be understood by reference to the accompanying drawing, which represents, 70 in vertical longitudinal section, a pressure-regulator embodying my invention.

A represents the case of the regulator-valve, which, in the present instance, is a "balance-plunger," so called, the inlet of such valve-case being shown at B, its ports at E F, and valves at a d, while its eduction or discharge is at C.

The pipe c is connected at its farther end with the operating machine, and at its near 80 end with the regulator through the opening b. The lower portion of said regulator contains the flexible diaphragm J, fastened in the usual manner, and, in connection with the lever o and weights attached to the lower portion of 85 the valve-stem K, reducing as much as may be desired the pressure from the main boiler.

I obtain access to the interior of the water-well H and to the valve-stem K by means of the orifice b and plug e, and by inserting a pin 90 or rod in the hole s in such stem I prevent the latter from rotating while the nut is put on or removed from its lower end.

The parts thus far described are substantially like those described in my Letters Patent No. 161,917, dated April 13, 1875, reissued 95 March 12, 1878, No. 8,124.

In applying my improvement to this form of regulator I make in the shell of the apparatus, between the lower end of the water-well H and the diaphragm-chamber L, a cylindrical chamber, I, and in this cylinder I place a loose-fit-

ting piston, D, which is mounted on and connected with the valve-stem K in any suitable manner. The piston should be of smaller area than the diaphragm, and, as above stated, fits 5 in its cylinder loosely, so that water may be free to pass above and below it. Under these conditions the pressure of water due to the steam-pressure will be exerted on both faces of the piston, and will act on the diaphragm 10 as usual. When there is increased pressure the water will, under that pressure, pass by the piston from the water-well into the diaphragm-chamber, and act on the diaphragm with the result of partly closing the valve. 15 When, on the other hand, pressure in the water-well decreases, pressure in the diaphragm-chamber will in like manner decrease, and the weighted lever will act to raise the diaphragm, the water thus displaced passing readily from 20 the diaphragm-chamber, by the piston, into the well.

In case the diaphragm should, from any cause, be torn or fractured, the water from the water-well will pass out through the opening in 25 the diaphragm, and the piston will be subjected to direct steam-pressure, which will act to force the piston down, and thus close the valve to such an extent as to prevent the pressure in the apparatus supplied by the regulator 30 from becoming excessive.

The objection to pistons being used solely in pressure-regulators in place of diaphragms is as follows: If the piston is fitted into the cylinder so that it will not leak steam or water 35 it is then so tight that it will not work easily enough to maintain a uniform pressure in the apparatus to which it is attached. If, on the contrary, the piston is fitted into its cylinder loosely enough to work easily and maintain a 40 uniform pressure in said apparatus it will leak steam or water so that there will be a great waste, and the differential expansions caused by steam leaking through it to the atmosphere would be another detriment to its working; 45 but by combining the piston with a diaphragm, as hereinbefore described, I entirely overcome this objection. As the piston lies between the lower end of the water-well and the diaphragm-chamber, it will always be submerged in water 50 when the diaphragm is free from fracture, therefore overcoming to a great extent the differential expansion before alluded to, water being an excellent medium for keeping all the parts at the same temperature.

55 By my present improvement I also dispense with the shelf or partition at the bottom of the water-well, (shown in my Letters Patent above named, and also in my Letters Patent No. 146,153, of January 6, 1874,) so that the piston 60 will receive the full pressure from the appa-

ratus instantly in case the diaphragm bursts, which would not be possible were the said shelf or partition retained.

To enable others to understand more fully the workings of a pressure-regulator of the 65 class here shown with my present improvement added, we will suppose that a regulator is attached with my present improvement to heat the cylinders of a "slasher-machine," so called, such as are generally used in cotton-mills, and that the regulator is weighted so as to maintain in the cylinders of said slasher-frame a pressure of six pounds to the square inch. If the slasher is run faster or the yarn contains more moisture, the pressure in said 75 cylinders will be slightly lowered. Consequently the pressure in the water-well H and diaphragm-chamber L will be lowered, thus allowing the weighted lever o to open the regulator-valve, and through its ports E F admit 80 more steam to the cylinders. When the pressure has risen to its maximum amount in said cylinders, the pressure acts back through the independent pipe e upon the column of water in the water-well, and through it upon the diaphragm, passing the piston D and raising the weighted lever and partially or entirely closing the regulator-valve. So long as the diaphragm is free from fracture the pressure upon the upper and under sides of the piston D is 85 90 practically equal; but should the diaphragm burst, the pressure then acts upon the piston. Inasmuch as the latter is of smaller area than the diaphragm, the pressure in the cylinders will rise somewhat—say, to nine pounds or 95 thereabout—before it can operate the piston to close the regulator-valve; but if the piston were not there at all, the full boiler-pressure would be let into the cylinders and in many cases would burst them. 100

I do not wish to restrict myself to the form of regulator herein shown, as my improvement may be applied to any regulator whatsoever capable of accomplishing the same result.

What I claim, and desire to secure by Letters 105 Patent, is—

In a pressure-regulator, the combination, with a regulator-valve, water-well, flexible diaphragm, and weighted lever or spring, of a piston smaller in area than said diaphragm, connected to the valve and applied between the bottom of the water-well and the diaphragm-chamber, as and for the purposes herein described.

In testimony whereof I affix my signature 115 in presence of two witnesses.

JOSEPH E. WATTS.
